UNITED STATES PATENT OFFICE.

WADE H. HARRISON, OF PETERSBURG, VIRGINIA.

GARMENT-HANGER-SUPPORTING MEANS FOR WARDROBE TRUNKS.

Application filed October 4, 1924. Serial No. 741,657.

This invention relates generally to improvements in trunks of the wardrobe type and has reference more particularly to a means for supporting a garment hanger bar 5 in one of the sections or body of the trunk.

One of the important objects of the present invention is to provide a garment hanger bar supporting means wherein the same is normally disposed within the trunk when 10 the latter is closed, the means being adapted to be swung outwardly from the trunk body in a plane substantially parallel to the open side thereof in order to permit ready access to the garments supported on the bar.

15 A further object of the invention is to provide a garment hanger supporting means of the above mentioned character, which includes certain improvements over my co-pending application for a garment hanger 20 supporting mechanism for wardrobe trunks, filed January 18, 1924, and bearing Serial No. 687,053.

A still further object is to provide a garment hanger supporting means of the above 25 mentioned character, which is simple in construction, inexpensive, strong and durable and furthermore adapted for the purposes for which it is designated.

Other objects and advantages of this invention will become apparent during the course of the following description.

In the accompanying drawing forming a part of this specification and in which like numerals designate like parts throughout 35 the same:

Figure 1 is a top plan view of the body of the trunk with the top removed showing my invention in position therein.

Figure 2 is a rear elevation of the bar supporting arm showing the same in position within the trunk body.

Figure 3 is a detail elevational view of the bracket associated with the arm showing the same supported on the U-shaped member, and

Figure 4 is a detail view showing the garment hanger supporting bar in a downwardly inclined position.

In the drawing wherein for the purpose 50 of illustration is shown the preferred embodiment of my invention, the numeral 1 designates generally one of the sections of a well known type of wardrobe trunk which is open at its front side, the other section 55 forming a closure for the section 1 being hinged at 2 to one of the side edges of the

section 1. The closure section is indicated at 3.

A substantially U-shaped bracket 4 has the arm 5 thereof provided with the enlarged portion 6 which is in turn provided with an opening through which extends the pivot pin 7. The lower end of the pin is provided with a rounded head 8 which rests on a plate 9 supported on the block 10 the 60 inside wall of the trunk body 1 adjacent the free open end thereof and also adjacent the top. The upper end of the pivot bolt 7 extends into a suitable block 11 secured on the under side of the top of the trunk 1 adjacent the side wall 12. The other arm 13 the 65 of the U-shaped bracket 4 has extending upwardly from the free end thereof the substantially rectangular shaped block 14 and the same provides a means for rigidly supporting the garment hanger supporting arm 15 at one end thereof.

A bracket 16 is secured to the inner face of the arm 15 and the same is of such construction as to fit over the block 14 and also 80 over the end of the arm 13, the bracket being cut away as illustrated at 17 to facilitate the end of the arm being properly supported on the arm 13 of the U-shaped bracket 4.

The arm 15 carries on the intermediate portion thereof the bracket designated generally by the numeral 18. Also associated with the bracket 18 is the garment supporting bar designated generally by the numeral 90 19 and the same includes the hinged sections 20 and 21 respectively.

For the purpose of normally holding the arm 15 and the garment hanger supporting bar 19 within the trunk body 1, the free 95 end of the arm 15 carries thereon a latch 22 of any well known construction, the same being adapted for cooperation with the keeper 23 secured to the opposite side wall of the trunk body. It is of course to be 100 understood that the bar 19 will be disposed in the position as shown in Figure 1 of the drawing so that the arm may be maintained in locked engagement with the trunk.

When it is desired to move the arm 15 105 outwardly from the trunk in order to obtain access to the garment supported on the hanger bar 19, the latch 22 is disengaged from the keeper 23 and the arm is swung outwardly in a horizontal plane in such a 110 manner as to cause the U-shaped bracket 4 to swing around the free edge of the side

wall 12 of the trunk so that the arm 15 may be disposed in a plane substantially parallel to the open front side of the trunk. The bar 19 may then have the section 21 thereof 5 swung into alignment with the section 20 and if desired, the bar 19 may be tilted to the position as shown in Figure 4 of the drawing. By permitting the arm 15 to be swung into such a position, access to the 10 trunk may be easily obtained as well as permitting ready and easy access to the garment supported on the bar 19.

When it is not desired to support the garment on the hanger bar in the trunk, the 15 arm 15 which carries the bar 19 may be readily disengaged from the block 14 on the U-shaped bracket 4 and by placing the bracket 16 of the arm 15 on a similar support to that illustrated at 14 and which may 20 be secured to the wall of a room on the inside of a door, the arm 15 may be attached thereto and supported in such position as to permit the garment on the hangers which are suspended from the hooks 24 of the bar 25 19 to hang properly from the supporting means.

It will thus be seen from the foregoing description, that a garment hanger supporting means has been provided which may be 30 readily incorporated with a wardrobe trunk or may be removed therefrom and supported in a closet. The simplicity in which my device is constructed enables the same to be easily and readily actuated.

35 While I have shown the preferred embodiment of my invention, it is to be understood

that various changes in the size, shape and arrangement of parts may be resorted to without departing from the spirit of the invention and the scope of the appended 40 claims.

Having thus described my invention, what I claim is:—

1. A garment hanger supporting means for wardrobe trunks; wherein the trunk has 45 a side opening, including a vertical pivot pin supported in the trunk at one end of the side opening, a U-shaped bracket having its plane horizontally disposed, one end of the bracket mounted on the pivot pin, a block 50 rising from the other end of the bracket, a garment hanger supporting arm, and a member secured to the arm and adapted to engage over the block.

2. A garment hanger supporting means 55 for wardrobe trunks; wherein the trunk has a side opening, a block supported adjacent one of the upper corners of the opening in the trunk, a U-shaped bracket having its plane horizontally disposed, a pivot pin 60 piercing one end of the bracket and extending into the block, the lower end of said pin having a head, a block supported in the trunk below the first mentioned block, a plate on the second mentioned block engaging the head of the pivot pin to hold it in place, and a garment hanger supporting arm engaged with the other end of the U-shaped bracket.

In testimony whereof I affix my signature.

WADE H. HARRISON.
